M. HARRISON
DISPENSING CABINET

Des. 166,310

Filed Sept. 12, 1951

INVENTOR.
MARY HARRISON
BY Edward B. Fogg

UNITED STATES PATENT OFFICE

166,310

DISPENSING CABINET

Mary Harrison, Oakland, Calif.

Application September 12, 1951, Serial No. 16,616

Term of patent 14 years

(Cl. D52—3)

To all whom it may concern:

Be it known that I, Mary Harrison, a citizen of the United States of America, residing at city of Oakland, county of Alameda, State of California, have invented a new, original, and ornamental Design for Dispensing Cabinet, of which the following is a specification, reference being had to the accompanying drawing, forming a part hereof.

Figure 2 is a perspective view showing the rear and the other side of said dispensing cabinet.

I claim:

The ornamental design for a dispensing cabinet, as shown.

MARY HARRISON.
